Primary Examiner — Katherine A Holbrow*Assistant Examiner* — Erin F. Keister(74) *Attorney, Agent, or Firm* — Morgan, Lewis & Bockius LLP(57) **CLAIM**

The ornamental design for a display screen with graphical user interface, as shown and described.

DESCRIPTION

The FIGURE is a front view of an image for a display screen with graphical user interface showing our new design. The peripheral dash-dot-dash lines illustrate a display screen or portion thereof and form no part of the claimed design. The broken lines illustrate features that form no part of the claimed design.
